UNITED STATES PATENT OFFICE.

SIMON BRALOVE, OF WASHINGTON, DISTRICT OF COLUMBIA.

WRENCH.

1,320,730.

Specification of Letters Patent.

Patented Nov. 4, 1919.

Application filed February 25, 1919. Serial No. 279,054.

To all whom it may concern:

Be it known that I, SIMON BRALOVE, a citizen of the United States, residing at Washington, in the District of Columbia, have invented certain new and useful Improvements in Wrenches, of which the following is a specification.

This invention relates to wrenches, and more particularly to that class of wrenches which are gear-operated.

The present invention has for its objects, among others, to provide an improved wrench of this general type, adapted more especially for use in connection with the nuts upon automobiles or the like, and especially adapted for use in operating on nuts that are in out-of-the-way or inaccessible places, hard to get at with the ordinary form of wrench.

20 A primary object of the present invention is to provide a wrench having means whereby the end thereof may be securely held in position so that both hands of the operator will be free for manipulation of the wrench. 25 To this end the body portion of the wrench is extended a considerable distance and the end thereof provided with an offset, with a stud or pin in said offset, for a purpose which will be hereinafter more fully explained.

30 Other objects and advantages of the invention will hereinafter appear, and the novel features thereof will be specifically defined by the appended claims.

35 The invention is clearly illustrated in the accompanying drawings, which, with the numerals of reference marked thereon, forms a part of this specification, and in which—

Figure 1 is a side elevation of a portion of 40 the crank case of an automobile, with portions broken away and parts in section, showing one mode of use of my improved wrench.

45 Fig. 2 is a side elevation of the wrench. Like numerals of reference indicate like parts in the different views.

Referring to the drawings the wrench is shown as composed of two flat metal plates 1 and 2. These two plates, which may be 50 of a thickness and width in accordance with the strength required, or the uses to which the wrench is to be put, are disposed parallel with each other and in contact throughout the greater portion of their length, being secured together by suitable means as the rivets or the like 3 and 4, as shown. The plate

1 is of less length than the plate 2 and the rivet 4 is placed adjacent the end of the plate 1, as seen in both views.

The rivet or other securing means 3 is placed at a distance from the other end of the plate 1, and adjacent said rivet the plate 1 is provided with an offset or band 5 as seen best in Fig. 1, to provide a space between the two plates, and in this space are disposed two gears 7 and 8, although more than two may be employed when desired. These gears have their shafts mounted to revolve in the plates 1 and 2, the shaft 9 of the gear 7 being clearly seen in Fig. 2. These 70 gears mesh with each other as shown, and the shaft of the gear 7 has a polygonal opening into which is received the correspondingly-shaped end of the stem 10 of the handle by means of which the said gear is revolved.

The gear 8 has its hub provided with an opening in which is received the shank 11 of the wrench block, said shank extending through the hub or shaft of the gear 8 and receiving a washer or the like 13 and a cotter pin or the like 14 by which the shank is held against displacement. By turning the handle 15 the gear 7 is rotated and this in turn revolves the gear 8 and consequently the 85 wrench block 12.

The end of the plate 2 opposite the end to which the gears are applied is extended beyond the plate 1 as seen in Figs. 1 and 2 and just beyond the end of the plate 1 the plate 2 is deflected or provided with a bend 16 so as to bring the plane of the end of the plate 2 out of the plane of the plate 1 for a purpose soon to appear, and this free end of the plate 2 is provided with a stud or pin 17 as seen 95 best in Fig. 1.

Fig. 1 illustrates the use of my improved wrench in taking off or applying the nut 18 within the crank case 19 of an automobile. The end of the wrench carrying the gears is 100 placed through the opening 20, after the lower cover plate of the crank case has been removed, and pushed endwise till the wrench block comes in proper position to engage the nut and then the stud 19 is engaged in the hole 21 from which one of the bolts that secured the said cover plate in position has been removed, and the wrench is thus held against endwise movement without further means. The handle projecting through the 105 opening in the bottom of the crank case 110 serves to give the necessary rotation to the

gear 7 and to the gear 8 and in this way the nut is turned one way or the other without difficulty.

The end of the plate 2 has a firm bearing 5 against the bottom of the crank case and the offset or bend 16 brings the plates in proper position so as to maintain a parallel horizontal position and binding of the gears is prevented.

10 Modifications in detail may be resorted to without departing from the spirit of the invention or sacrificing any of its advantages.

What is claimed as new is:—

15 1. A gear-operated wrench having its gear-carrying members extended and at one end provided with a projecting member for centering the wrench with respect to the nut to be engaged and for holding the wrench against endwise movement.

20 2. A gear-operated wrench having its gear-carrying members extended and provided with an offset and means projecting from the end of the body portion for engagement in an opening to center the wrench with respect to the nut to be engaged and to hold the wrench against endwise movement.

25 3. A gear-operated wrench comprising plates arranged parallel with each other and in contact with each other for a major portion of their length, one of said plates being

offset adjacent one end, gears disposed in the space between said plates at the offset end, and a wrench block carried by one of said gears, the other end of one of said plates being provided with a stud for engagement in an opening to prevent endwise movement of the wrench.

4. A gear-operated wrench composed of plates secured together with the plates in contact with each other for a major portion 40 of their length, said plates provided at one end with intermeshing gears disposed in the space between said plates, and the other end of one of said plates being provided with a laterally-projecting stud.

45 5. A gear-operated wrench composed of plates forming the body portion of the wrench, one of said plates being offset at one end and the other plate offset in the opposite direction at the other end of the body portion, coöperating gears in the space between the plates at one end, and a stud projecting from the end of one of the plates at the other end of the body portion.

50 In testimony whereof I affix my signature 55 in the presence of two witnesses.

SIMON BRALOVE.
